UNITED STATES PATENT OFFICE.

GEORGE HULUDET, OF CANTON, OHIO.

CIGARETTE-HOLDER.

1,286,643.

Specification of Letters Patent.

Patented Dec. 3, 1918.

Application filed August 2, 1918. Serial No. 247,994.

To all whom it may concern:

Be it known that I, GEORGE HULUDET, a citizen of the United States, residing at Canton, in the county of Stark and State of Ohio, have invented new and useful Improvements in Cigarette-Holders, of which the following is a specification.

This invention relates to smokers' articles, particularly to cigarette holders, and has 10 for its object the provision of a device in which a cigarette may be held while it is being smoked, the cigarette being at all times inclosed so as to eliminate all danger caused by the dropping of ashes and sparks, 15 the device being particularly adapted for indoor use or in the vicinity of inflammable material.

An important object is the provision of a cigarette holder of this character in which 20 the cigarette will be positively held in spaced relation to the walls thereof so as to provide an ash receiving space entirely surrounding the cigarette.

A further object is the provision of a device 25 of this character in which the cigarette is at all times entirely inclosed, the device being so formed that the cigarette may be lighted without opening the inclosing receptacle.

Still another object is the provision of a 30 device of this character in which one end is removable for insertion of the cigarette and the removal of the ashes, the removable end carrying a peculiarly constructed holding 35 member engageable about the cigarette for properly positioning the cigarette within the device.

An additional object is the provision of a 40 holder of this character which will be comparatively simple and inexpensive in manufacture, highly efficient in use, durable in service and a general improvement of the art.

With the above and other objects and advantages in view, the invention consists in the details of construction to be hereinafter more fully described and claimed, and illustrated in the accompanying drawings in which:—

50 Figure 1 is a longitudinal sectional view illustrating the preferred form of my invention.

Fig. 2 is an end elevation thereof.

Fig. 3 is a longitudinal sectional view 55 showing a slightly modified form.

Fig. 4 is an elevation of the closure caps

shown in Fig. 3, the wire mesh being removed.

Referring more particularly to the drawings and especially to Figs. 1 and 2, the numeral 10 designates the inclosing shell of my device which may be formed of sheet metal, wood, fiber or any other suitable material and which has its outer end provided with a reduced extension 11. The shell 10 is provided throughout the major portion of its length with a chamber 12 which communicates to the other end of the shell with a reduced chamber 13 communicating with an opening 14 extending to the end of the shell. The opening 14 is threaded as shown for engagement therein of a threaded extension 15 on the end of an ordinary form of mouth piece 16 which may be formed of bone, celluloid, amber or other suitable material.

In order that the outer end of the shell 10 may be substantially closed, I provide a cap 17 which is formed as a disk 18 having a peripherally extending flange 19 engaged upon the reduced extension 11 at the end of the shell. The disk 18 is provided with a plurality of perforations 19 through which air may enter the shell so as to promote combustion of the cigarette.

In order to provide means whereby a cigarette, designated by the letter A may be properly positioned within the shell, I provide a pair of spring clamping members 20 formed preferably of metal, such as wire, which are disposed longitudinally within the shell 10 and which are secured upon the inner face of the disk 18 in any suitable manner as by soldering. The ends of the clamping members 20 are outwardly flared 95 as shown at 21 to facilitate the insertion of a cigarette therebetween.

Referring to Figs. 3 and 4 of the drawing in which I have shown a slightly modified form of the device, the numeral 22 designates 100 a closure cap which is provided with a centrally depressed portion 23 having a central opening 24. In this form of the device, the cap 22 is engaged upon the reduced extension 11 at the end of the shell 10 in exactly 105 the same manner as in the preceding form. In this instance however the cigarette A is adapted to have its extreme end pass through the central opening 24 and substantially in contact with a screen 25 of 110 wire mesh which extends across the depressed portion of the cap. Surrounding the

central opening 24, the depressed portion 23 is provided with a plurality of perforations 26 whereby air may be admitted to the interior of the shell 10. In this form, the 5 spring clamping members 20 are soldered or otherwise secured upon the depressed portion 23 of the cap.

In the use of either form of the device, the cap 17 or 22 as the case may be is removed 10 and the cigarette is inserted between the spring clamping members 20. The cigarette and the clamping member 20 are then passed into the interior of the shell 10 and the end of the cigarette engaged within 15 the recess 13 while at the same time the cap is engaged upon the reduced extension 11 at the end of the shell. When the operator places the bit or mouth piece 16 in his mouth, and draws upon the device, the cigarette may 20 be readily lighted by holding a match adjacent the closure cap. In view of the fact that air can enter through either the cap 11 or 22, as the case may be, the cigarette may burn freely and evenly until entirely consumed, after which the cap is removed and 25 the ashes dumped out of the shell.

From the foregoing description and a study of the drawing it will be apparent that I have thus provided a very simple and 30 inexpensive cigarette holder which will entirely inclose the cigarette while it is being consumed and which will effectively hold the ashes and sparks so that danger of fire from smoking near combustible materials 35 will be prevented, the device being further advantageous in preventing the objectionable spilling of ashes within doors.

While I have shown and described the preferred embodiment of my invention, it 40 will of course be readily understood that I

reserve the right to make such changes in the form, construction and arrangement of parts as will not depart from the spirit of the invention nor the scope of the subjoined claims.

45

What is claimed is:—

1. A device of the character described comprising a hollow shell provided at its inner end with a recess, a mouth piece connected with one end of said shell and provided with a bore communicating with said recess, a cap detachably mounted upon the other end of said shell and provided with perforations, and a pair of spaced clamping members secured to said cap and extending longitudinally within said shell, said clamping members being adapted to engage a cigarette and said recess receiving the inner end of the cigarette.

50

2. A device of the character described comprising a hollow shell provided at one end with a recess, a mouth piece detachably connected with one end of said shell and provided with a bore communicating with said recess, a flanged cap detachably engaged upon the other end of said shell and having its central portion depressed and provided with a relatively large central hole surrounded by an annular series of relatively small perforations, a pair of spaced clamping members secured upon the inner side of said depressed portion and extending longitudinally within said shell, and a screen secured upon said cap and bridging said depressed portion, said clamping member being adapted to engage a cigarette and said hole and said recess receiving the ends of the cigarette.

55

In testimony whereof I affix my signature.
GEORGE HULUDET.
